COMBINATION KITE CONTROL
STICK AND WINDER

Donald J. Kennedy, 6318 Camelia St.,
North Hollywood, Calif. 91344

Filed June 16, 1967, Ser. No. 7,503

Term of patent 14 years

(Cl. D41—1)

FIG. 1.

FIG. 2.

FIG. 3.

FIG. 4.

FIG. 5.

FIGURE 1 is a perspective view of a combination kite control stick and winder showing my new design;

FIGURE 2 is a front elevational view thereof;

FIGURE 3 is a top plan view thereof;

FIGURE 4 is a bottom plan view thereof; and,

FIGURE 5 is an end view thereof.

The dotted line showing of a portion of a string on the stick of FIGURE 1 is for illustrative purposes only.

I claim:

The ornamental design for a combination kite control stick and winder, substantially as shown and described.
